A. GÜNTHER ET AL
HEAT INSULATING BOTTLE

Filed June 8, 1926

Inventor:

Albert Günther, Richard Geeloff
Jno. Minic
Attorney:

UNITED STATES PATENT OFFICE.

ALBERT GÜNTHER AND RICHARD GERTLOFF, OF SCHMIEDEFELD IN THURINGEN,
GERMANY.

HEAT-INSULATING BOTTLE.

Application filed June 8, 1926, Serial No. 114,450, and in Germany March 4, 1926.

Our present invention has for its object to provide an improved heat insulating bottle, which has many advantages over insulating bottles heretofore used.

5 In the bottle according to our invention the glass is made thick where the bottle is submitted to a maximum strain, whereas in known insulating bottles the contrary will be found, whereby many bottles will be 10 broken already in the assembling operation.

Our improved insulating bottle is illustrated by way of example in the accompanying drawing, an elevation, partly in section of the bottle.

15 The bottle has a reinforcing portion *a* serving to resist to the threaded ring *b*. Said ring is provided with screw-threads and will be engaged upon the bottle from below, so that said ring will be tightened upon the 20 reinforced portion *a* of the bottle. Now as the ring *b* owing to the abrupt reinforcing of the glass of the bottle has a larger periphery than the glass itself, it will occur that owing to the threaded cap *c*, which will 25 be threaded onto the ring *b*, the glass bottle will be freely suspended within the sheet-iron casing *d*. Upon tightening the threaded cap *c*, the ring *b* will be firmly tightened upon the reinforced portion *a* of the bottle.

30 Now the whole will be screwed into the protecting casing *d* and thus, owing to the large clearance between the glass bottle and protecting casing, which is the same at the bottom, the glass bottle will be safe not only 35 when assembling the parts but also when shocks are produced. In most structures of this kind the insulated bottles rest on cork. Now if a pressure is produced upon the bottle from the top thereof, as will be 40 the case by inserting the stopper into the same, the cork arranged on the bottom of the protecting casing will yield in most cases with the result that the discharge nipple *f* will be broken off. The device is further 45 more provided with a protecting cap *e* screwed onto the cap *c*.

In our improved device the bottle may be easily and conveniently cleaned owing to the simplicity of construction thereof.

Having now fully described our said invention, what we claim and desire to secure by Letters Patent, is:

1. In an insulating bottle, a glass bottle having the upper portion thereof thickened to present an outstanding reinforce, a ring 55 cooperating with the reinforce and having an internal diameter slightly less than the maximum external diameter of the reinforce, whereby the ring can only engage with the reinforce from the bottom of the bottle, 60 and a casing cooperating with the ring and binding the same upon the reinforce.

2. In an insulating bottle, a glass bottle having the upper portion thereof thickened to present an outstanding reinforce, a ring 65 cooperating with the reinforce and having an internal diameter slightly less than the maximum external diameter of the reinforce, whereby the ring can only engage with the reinforce from the bottom of the bottle, 70 and a casing cooperating with the ring and binding the same upon the reinforce, said casing being spaced from the bottle throughout the full length of the latter below the 75 ring.

3. In an insulating bottle, a glass bottle having the upper portion thereof thickened to present an outstanding reinforce, a ring 80 cooperating with the reinforce and having an internal diameter slightly less than the maximum external diameter of the reinforce, whereby the ring can only engage with the reinforce from the bottom of the bottle, a cap carrying section having threaded connection with the ring, and a casing having 85 threaded connection with the cap carrying section and enclosing that portion of the bottle below the ring.

In testimony whereof we have hereunto set our hands.

ALBERT GÜNTHER.
RICHARD GERTLOFF.
